UNITED STATES PATENT OFFICE.

VELMA MILLER CLARK, OF BREA, CALIFORNIA.

DESIGN FOR AN APRON.

Application filed January 12, 1926. Serial No. 16,032. Term of patent 3½ years.

To all whom it may concern:

Be it known that I, VELMA MILLER CLARK, a citizen of the United States, residing at Brea, in the county of Orange and State of California, have invented a new, original, and ornamental Design for an Apron, of which the following is a specification, reference being had to the accompanying drawing, forming part thereof.

The figure is a perspective view of an apron embodying my design.

I claim:

The ornamental design for an apron, as shown.

VELMA MILLER CLARK.
